UNITED STATES PATENT OFFICE.

JOHN D. MILLER, OF WASHINGTON, DISTRICT OF COLUMBIA, ASSIGNOR OF ELEVEN-SIXTEENTHS TO FIRMAN R. HORNER, ALLEN S. JOHNSON, AND JERRY F. RITTER, OF SAME PLACE.

DESIGN FOR A BOTTLE OR JAR TOP.

SPECIFICATION forming part of Design No. 30,434, dated March 28, 1899.

Application filed March 3, 1899. Serial No. 707,678. Term of patent 14 years.

To all whom it may concern:

Be it known that I, JOHN D. MILLER, a citizen of the United States, residing at Washington, in the District of Columbia, have invented and produced a new and original Design for Bottle or Jar Tops, of which the following is a specification, reference being had to the accompanying drawings, forming part thereof.

- 10 Figure 1 is a top plan view of a bottle or jar top, showing my new design. Fig. 2 is a sectional view of the same on the line $x-x$, Fig. 1. Fig. 3 is a sectional view of the same on the line $y-y$, Fig. 1.
- 15 As shown in the drawings, the leading or material features of my design consist of the upwardly-projecting edges 1 along the side of said top, said edges being struck up at an

angle less than a right angle, and the central struck-up heart-shaped portion 2 in the center 20 of said top. The front edge of the top is also provided with a struck-up edge 3, similar to but not as high as the side edges 2. The top also has a slight indentation back of the heart-shaped struck-up portion, and the rear 25 end of the top is contracted or tapered to form a handle 4.

Having described my invention, what I claim as new, and desire to secure by Letters Patent, is—

The design for a bottle or jar top, as herein shown and described.

JOHN D. MILLER.
